HAIRBRUSH

Kenneth C. Fay, New York, N. Y.

Application November 4, 1952, Serial No. 22,122

Term of patent 7 years

(Cl. D86—10)

To all whom it may concern:

Be it known that I, Kenneth C. Fay, a citizen of the United States, residing at New York, in the county of New York and States of New York, have invented a new, original, and ornamental Design for a Hairbrush, of which the following is a specification, reference being had to the accompanying drawing, forming part thereof.

In the drawing:

Fig. 1 is a top plan view of the hairbrush, showing my new design;

Fig. 2 is a side elevational view of the same;

Fig. 3 is a bottom view of the same;

Fig. 4 is a vertical sectional view taken on the line 4—4 of Fig. 1; and

Fig. 5 is a vertical sectional view taken on the line 5—5 of Fig. 1.

I claim:

The ornamental design for a hairbrush, as shown.

KENNETH C. FAY.
